A. TREW, OF UNION CITY, INDIANA.

Letters Patent No. 87,888, dated March 16, 1869.

IMPROVEMENT IN STEAM-ENGINE OSCILLATING VALVES.

The Schedule referred to in these Letters Patent and making part of the same.

To all whom it may concern:

Be it known that I, A. TREW, of Union City, in the county of Randolph, and State of Indiana, have invented certain new and useful Improvements in Conical Oscillating Valves for Steam-Engines; and I do hereby declare that the following is a full and exact description thereof, reference being had to the accompanying drawings, making a part of this specification.

The nature of my invention relates to an improvement in conical oscillating valves for steam-engines, whereby the steam is admitted continuously from the steam-chest through an opening in the end of the valve, thus obviating the difficulty arising from the inequality of pressure within the valve, consequent upon allowing the steam to be exhausted and replenished at intervals.

Also, my invention further consists in providing set-screws, at either end of the valve, by means of which the same may be adjusted to its proper place in the barrel, either to counteract the effects of wear, or of the expansion of the valve by heat.

To enable others skilled in the art to make and use my invention, I will proceed to describe the same with reference to the drawings, in which—

Figure 1 is a longitudinal section, and

Figure 2 is a vertical cross-section of my improved valve.

Figure 3 represents the plate used to prevent the egress of steam through the opening that admits the supply-pipe from the steam-chest.

A represents a hollow conical valve, suspended in the barrel W, by means of the set-screw T and the shaft R, which latter passes through the packing-box G, and is provided with a crank, D, to which a straight rod from the eccentric is attached, for moving the valve.

The supply-pipe U communicates with the steam-chest, and is introduced into the valve, through the curved slot S, shown by dotted lines.

Egress of steam through the slot S, is prevented by the plate E, which is fitted closely to the end of the valve, and is held in place by the pressure of the steam.

For convenience in introducing plate E, the cap, C, of the valve may be secured in its place by screws.

The ports I I and J J are designed to admit steam to the cylinder, and

K K is the escape, or eduction-opening.

It will be observed that these openings are so arranged as to require the minimum of oscillation of the valve.

It has been found in practice that a valve of this description is expanded by the heated steam within it to a much greater degree than the surrounding barrel; consequently, when well fitted, it is liable to stick.

To obviate this difficulty, as also to provide for the wear of the valve, is the object of the set-screws L and T.

These screws impinge upon the shaft R and the centre of the valve, at X, and afford a convenient means of adjusting the said valve to any required position.

Having thus fully described my said invention,

What I claim, and desire to secure by Letters Patent, is—

In combination with the conical oscillating valve A, the supply-pipe U and plate E, when arranged and constructed substantially as herein set forth.

A. TREW.
